UNITED STATES PATENT OFFICE.

CARL WENNHOOLD, OF REDMOND, OREGON.

REFRIGERATING APPARATUS.

1,250,062.

Specification of Letters Patent. Patented Dec. 11, 1917.

Application filed February 9, 1917. Serial No. 147,640.

To all whom it may concern:

Be it known that I, CARL WENNHOOLD, a citizen of the United States, residing at Redmond, in the county of Deschutes and State 5 of Oregon, have invented new and useful Improvements in Refrigerating Apparatus, of which the following is a specification.

This invention relates to refrigeration, and more especially to automatic control; 10 and the object of the same is to provide means whereby the operation of the machine will be regulated and controlled and the pressure will be prevented from reaching a dangerous height, while yet keeping the machine 15 working at full capacity. This leaves the engineer free to perform other duties or attend to other machinery, and economizes labor to the extent that the exclusive attention of one operator is not required. Details 20 are set forth in the following specification and claims, and shown in the accompanying drawings wherein—

Figure 1 is a diagram of this plant complete.

Fig. 2 is a detail in section showing the 25 check valve and the reducing valve, the latter controlled by a thermostat and all contained in a separate casing.

Fig. 3 is a sectional detail of the pressure-controlled water valve.

Fig. 4 is a detail showing the latch for the belt-shifter, and the latch-tripping mechanism controlled by either of two valves.

The construction and operation of plants 35 of this character are so well understood that I have shown much of the same diagrammatically only in Fig. 1, and will describe it briefly as follows: The letter E designates expansion coils located within a suitable 40 chamber, indicated only by the dotted lines, and when the refrigerating liquid (which is usually anhydrous ammonia) is admitted to these coils and its pressure suddenly reduced, the liquid immediately boils or expands 45 into a gas and in so doing absorbs heat from the coils and the air surrounding them, and therefore produces refrigeration as well understood. The gas from these coils is led by my process next through a casing 50 containing gas controlling valves and lettered G in the diagram, thence to the compressor or pump P, and from the pump along a pressure line to the condenser C within whose coils it is acted on by a cooling 55 agent such as water which may also be circulated by the same pump. This con-

denses the gas into liquid ammonia, and the latter flows back again through the element G which it approaches under high pressure. Therein its pressure is suddenly reduced as 60 above explained, and thus the operation is continuous. The purpose of the present invention is to provide means for controlling the action of the pressure-reducing valve by a thermostat which is governed by the temperature of the gas pipe as explained below, to further control the flow of liquid ammonia by a check valve actuated by a belt shifter when the latter is moved, to cause the movement of this belt shifter by automatic means when it is tripped, to trip it by excessive pressure or excessive vacuum in the gas line leading to and from the compressor respectively, and to provide means (in case the above is not sufficient) to increase the flow of water to the condenser when necessity requires. These various objects are carried out by the mechanism described in detail below.

Referring first to Fig. 2 for details of the 80 element lettered G in Fig. 1, the gas line 1 from the expansion chamber leads through a casing 2 and it is continued in what I call the suction line 3 which leads thence to the compressor. Within said casing the pipe 1 85 passes alongside a thermal bar 4 fixed at one end and adapted to expand and contract under variations of temperature. Its other end is connected at 5 with a bell crank lever 6 pivoted at its angle at 7, and the remote 90 end of its long arm is pivotally connected at 8 with the stem 9 of a check valve 10 which is located in the pipe 11 through which liquid ammonia flows. When now the bar 4 expands considerably, due to abnormal 95 heat in the pipe 1, the valve 10 is opened; but when it contracts as the temperature falls, said valve is closed more and more, and finally closed altogether. Within said casing 2 and on the pipe 11 is also located the 100 check valve 20' whose stem 19 is connected with a lever 16 pivoted at 17 as also seen in Fig. 2, and when this lever is depressed the check valve completely cuts off the flow of the ammonia to the expansion coils. Thus 105 the single casing may well be used to inclose the reducing valve 10 and the check valve 20', the former operated thermostatically and the latter operated by movement of the belt shifter as will be described below.

The compressor P may be of any suitable construction, its details forming an im-

portant feature of the present invention, save that I would have it made in pump form driven from a suitable source of power, not necessary to illustrate, by clutch mechanism or by fast and loose pulleys *f* and *l* as shown. In effect it is a pump creating suction on the line 3 and drawing the refrigerating agent in gaseous form from the expansion coils, conveying it through a 10 vacuum pipe 20, thence through a pressure pipe 21, and thence along the pressure line pipe 22 into the coils 23 of the condenser C. After having been condensed in the latter, it collects within a receiver 24, from 15 which it passes through the outlet 25 to the pipe 11 above referred to, and flows through the gas controller G back to the expansion chamber E.

The vacuum pipe 20 passes through a casing whereof one wall is a diaphragm 30, and the pressure pipe 21 also passes through a casing whereof one wall is a diaphragm 31. These diaphragms are respectively connected by links 32 and 33 with a latch 34 which is normally engaged with a catch 35 on a clutch actuator, or, as shown, a belt shifter 36 whose fork 37 stands astride the belt which leads to the fast and loose pulleys *f* and *l*; and this shifter is normally 25 projected in one direction by automatic means such as a spring 38. The arrangement of parts is such that when the latch is tripped the belt is moved to the loose pulley, and the diaphragms are of such resisting 30 power to vacuum and pressure respectively, that they draw on their links only when excessive or unusual conditions are reached. Finally a flexible member such as a cord 39 leads from the belt shifter through a fixed 35 eye at some point within the casing of the compressor P, and upward to the lever 16 of the check valve 20 above described. Therefore when the belt is shifted and this cord is drawn upon, the check valve closes to absolutely 40 stop the flow of liquid ammonia from the compressor to the expansion chamber.

A suitable pump may force water through the water pipe 40 which in the diagrammatic illustration is led through the coils 23 of the condenser for converting the gas in said coils into liquid ammonia as stated above; and at a point preferably adjacent the compressor P I employ the water valve W as seen in detail in Fig. 3. This consists 50 of a globe valve 41 let into the water pipe 40 and having its stem 42 connected with a lever 43 which is attached at one end to a fixed pivot 44. The other end of the lever is connected by a link 45 with a diaphragm 46 55 forming one side of a chamber which is in communication with the gas pressure line 22 as seen. This diaphragm is so set that when the pressure rises in said chamber the diaphragm, through the link 45 and lever 43, 60 moves the valve 41 to control the flow of

water. It is to be understood that many details are shown diagrammatically only, and I purposely omit those which relate to the pump structure or compressor, as these details form no part of the present invention. 70 With this construction of the parts of the plant and connections the operations of the whole is as follows:

When the proper liquids are supplied and the compressor started, frost forms on the 75 coils within the expansion chamber and refrigeration is produced as is usual. If the pressure should begin to climb, the first result is that more water is delivered to the water pipe 40 because the water valve W 80 within the pressure line 22 opens automatically as the pressure increases. If the additional water within the condenser is not sufficient and the pressure continues to climb, the diaphragm 31 within the pressure pipe 85 21 acts through its link 33 to lift the latch 34 and trip the belt shifter, which latter moves to throw the belt on the loose pulley *l* and stop the compressor. The engineer, even if he be away from his post, will be attracted by the stopping of the compressor, 90 and will of course return and restore the parts to their normal condition before shifting the belt back on the fast pulley *f* and causing the compressor to resume its action. 95 At the same time that the belt shifter moves, draft on the cord 39 closes the check valve 20 so that no more liquid ammonia is admitted to the expansion coils, but draft on this cord is released when the belt is restored to the fast pulley, and therefore this 100 valve is opened when the compressor is started up again. Shifting of the belt shifter also occurs in case excessive vacuum should prevail at any time within the vacuum pipe 105 20, for then its diaphragm 30 through its link will trip the latch 34 in the same manner. Meanwhile and at all times the reducing valve 10 is automatically controlled by the thermal bar through the bell crank lever 110 115 as clearly understood. I have found that with this invention applied to a small-sized plant, the constant attention of the engineer is not imperative and therefore he may use part of his time for other duties. I have 115 shown the gas valves G as located within a separate casing of their own, as I prefer, but this casing may be within the expansion chamber or at any convenient point. When the thermostatic regulator is properly adjusted, it will automatically control the reducing valve so that it will prevent the coils from becoming frosted up to a point too near the compressor, regardless of the temperature of the compartment or building 120 within which the system is located. When all the parts are adjusted properly the compressor is prevented from pumping liquid ammonia to the condenser C which of course is labor lost. As above suggested, the same 125 130

5 pump may control the flow of water, or it could be a separate pump connected with the shaft to which the fast pulley *f* is attached. I do not wish to be limited to the details of construction, as they are manifestly unimportant.

What is claimed as new is:—

- 10 1. In a refrigerating apparatus of the class described, the combination with an expansion chamber, a condenser, a compressor pump, a suction line leading from the expansion chamber to said pump, and a pressure line leading from the pump to said condenser; of fast and loose pulleys on the driving shaft of the compressor, a belt shifter therefor, means for normally moving it, a latch opposing said means, casings interposed in the suction and pressure pipes, one wall of each casing being movable, and links connecting the movable walls with said latch, for the purpose set forth.
- 15 2. In a refrigerating apparatus of the class disclosed, the combination with the expansion coils, the condenser coils, a line for the liquid refrigerant connecting said coils, and a check valve in said line; of a compressor, fast and loose pulleys on its operating shaft, a belt shifter therefor, means controlling the action of the belt shifter by an increase in pressure, and means whereby said

check valve is closed when the shifter is moved.

3. In a refrigerating apparatus of the class disclosed, the combination with the expansion coils, the condenser coils, a line for the liquid refrigerant connecting said coils, a reducing valve in said line, and a check valve also in said line; of a compressor, fast and loose pulleys on its operating shaft, a belt shifter therefor, means controlling the action of the belt shifter by an increase in pressure, and a cord connecting said belt shifter with the stem of said check valve, whereby the latter is closed when the shifter is moved.

4. In a refrigerating apparatus of the class disclosed, the combination with the expansion coils, the condenser coils, a line for the liquid refrigerant connecting said coils, and a check valve in said line; of a compressor, fast and loose pulleys, a belt shifter therefor, yielding means normally throwing said belt shifter, a latch opposing the action of said means, means controlled by the pressure for tripping said latch, and a flexible element connecting said shifter with the stem of the check valve whereby the latter is closed when the shifter is tripped.

In testimony whereof I affix my signature.

CARL WENNHOOLD.
